UNITED STATES PATENT OFFICE

141,969

DESIGN FOR A PERPETUAL CALENDAR

Simon H. Stupakoff, Latrobe, Pa.

Application May 26, 1945, Serial No. 119,749

Term of patent 14 years

(Cl. D74—5)

To all whom it may concern:

Be it known that I, Simon H. Stupakoff, a citizen of the United States, residing in Latrobe, in the county of Westmoreland and State of Pennsylvania, have invented a new, original, and ornamental Design for a Perpetual Calendar, of which the following is a specification, reference being had to the accompanying drawing, forming part thereof.

Fig. 1 is a front perspective view of a perpetual

calendar showing my new design, the numerals and printed matter being merely representative of that which will appear thereon from time to time.

Fig. 2 is a rear elevation; and

Fig. 3 is an end elevation.

I claim:

The ornamental design for a perpetual calendar, substantially as shown and described.

SEMON H. STUPAKOFF.
